UNITED STATES PATENT OFFICE.

PAUL E. THOKAR, OF PITTSBURGH, PENNSYLVANIA.

LIFE-SAVING DEVICE.

1,330,410.

Specification of Letters Patent. Patented Feb. 10, 1920.

Application filed March 20, 1919, Serial No. 283,795. Renewed December 24, 1919. Serial No. 347,196.

To all whom it may concern:

Be it known that I, PAUL E. THOKAR, a citizen of Bucowina, residing at Pittsburgh, in the county of Allegheny and State of 5 Pennsylvania, have invented certain new and useful Improvements in Life-Saving Devices, of which the following is a specification.

This invention relates to life saving devices, and has for its object to provide a device of such class, in a manner as herein-after set forth, with means adapted to be carried by and launched from a marine vessel and further capable of being extended to 15 form a hollow spherical buoyant structure providing a safe refuge for members of a crew or the passengers of the vessel in case the vessel is damaged or sinking, and further enable the persons housed within said 20 structure to be transported to another vessel or to the shore.

Further objects of the invention are to provide a life saving device which is simple in its construction, strong, durable, collapsible and extensible, efficient and convenient in its use, readily set up, and comparatively inexpensive.

With the foregoing and other objects in view the invention consists of the novel construction, combination and arrangement of parts as hereinafter more specifically described and illustrated in the accompanying drawings, wherein is shown an embodiment of the invention, but it is to be understood 35 that changes, variations and modifications can be resorted to which come within the scope of the claims hereunto appended.

In the drawings wherein like reference characters denote corresponding parts 40 throughout the several views:—

Figure 1 is an elevation of the device extended.

Fig. 2 is a sectional plan.

Fig. 3 is an elevation, broken away, of the 45 device collapsed or folded.

Referring to the drawings in detail the device comprises a frame formed of an inner, an intermediate and an outer annular member 1, 2 and 3 respectively. The members 1 and 2, are pivoted together, as at 4, and the members 2 and 3, are pivoted together as at 5, through the medium of an air conducting pipe 6, which extends through the said members 2 and 3, as well 55 as projecting above the member 3. The pipe 6, has its projecting portion looped as at 7,

so that it can be engaged by the elevating and lowering means for the purpose of raising the device from the water or for the launching of the device from a vessel or other support into the water. The looped portion 7, of the pipe 6, has a port 8 forming a discharge for water if it enters the outer or open end of the pipe 6, the latter furthermore is formed with air discharge ports 9 for the purpose of supplying air to the interior of the device or structure when the latter is extended.

The member 1 is formed at diametrically opposite points with a pair of oppositely disposed notches which are adapted to receive, when the frame is extended lugs 11, on the member 3, whereby the members 1, 2 and 3 are prevented from accidentally collapsing and are braced apart. The notches 10 are indicated at 10. The member 2 is furthermore provided with straps 12 which can be grasped by the people housed within the structure when the latter is extended.

The pivots 4, between the members 1 and 2 are formed from a pair of flanged sleeves 12', which extend through the members 1 and 2, and each of which forms a socket for a globular bearing 13, forming a universal joint. The inner face at each end 85 of a sleeve 12' is flaring in contour. Extending inwardly from the bearing 13 is an arm 14 provided with a socket 15 to receive the handle of an oar. Projecting outwardly from the bearing 13 is an arm 16, having a 90 socket 17 to receive the blade of an oar. The handle of the oar is indicated at 18 and is detachably connected in the socket 15. The blade of the oar is indicated at 19 and is detachably connected in the socket 17. The flared portions of the sleeves 12', at each end 95 thereof permit of the necessary sweep when operating the oars.

Arranged within the frame and connected together is a sectional floor or platform 100 which is formed of two sections 20 and 21, hinged together as at 22. The sections 20 and 21 are arranged within the member 2 and surround the lower portion of the pipe 6. The floor or platform is foldable and 105 when extended rests on the member 2. When the frame is extended the persons on the platform or floor can reach the straps 12.

The frame is inclosed by a flexible water proof covering 23, having a window 24, 110 and a door 25 so that access can be had to the structure when extended, and when the

- frame is extended the member 1 is disposed horizontally and within the member 2, the latter and member 3 are disposed vertically with the member 2 within the member 3.
- 5 When the members 1, 2 and 3, with the covering 23, are extended a hollow spherical buoyant structure is set up. The covering 23 is secured to the members 1, 2 and 3 in any suitable manner.
- 10 Suitable packings are provided at the joints between the pipe 6 and the members 2 and 3, and between the sleeves 12' and the members 1, 2 to prevent leakage. The position of the sleeves 12' is normally above the 15 water line. The floor or platform acts as a steady means when the device is launched and tends to keep the same upright in connection with the oars.

Packing is provided for the door 25 to 20 prevent leakage.

What I claim is:—

1. A life saving device comprising an extensible and collapsible frame formed of an inner, an outer and an intermediate annular

member pivotally connected together, said 25 frame being spherical in contour when extended, a water proof covering for said frame completely inclosing the frame, a pair of universal joints, each mounted in a pair of said members, oar handles detachably connected with said joints, oar blades detachably connected with said joints, and a sectional platform arranged within the frame.

2. A life saving device comprising an extensible and collapsible spherical frame 35 formed of an inner, an outer and an intermediate annular member pivotally connected together, an impervious covering completely inclosing said frame and formed of 40 flexible material provided with a door and a window, a pair of universal joints, each mounted in a pair of said members, oar handles and blades detachably connected with said joints, and a sectional platform ar- 45 ranged with said frame.

In testimony whereof I affix my signature.
PAUL E. THOKAR.
